ROAD JOINT FORMER WITH PLASTIC SUPPORT FOR FILLER BRIDGES

Robert R. Robertson, Chicago, Ill., assignor to
The Translode Joint Company, Chicago, Ill.,
a corporation of Illinois

Application July 13, 1934, Serial No. 734,911

17 Claims. (Cl. 94—51)

This invention relates to a concrete road expansion joint forming mechanism including filler supporting bridge means mountable in position to span an expansion joint void, and adapted to be supported in plastic supporting members releasably carried by a void forming core mechanism removable after the pouring of concrete, to form road sections separated by the expansion void the upper portion of which is closed by means 10 of a plastic filler deposited upon the bridge means in the expansion void.

It is an object of this invention to provide an expansion joint forming mechanism including a removable core unit having removably secured 15 thereon plastic supporting means adapted to be embedded in the concrete forming the road sections and being so positioned that the longitudinal margins of an arched filler supporting bridge means may be engaged therein to form a suitable support for a plastic filler for closing the upper portion of the expansion joint.

It is also an object of this invention to provide an expansion joint mechanism including a removable core as well as plastic supports removably supported on the sides thereof to be embedded in adjacent concrete road sections in a position to be accessible from the expansion void resulting from the removal of the core unit to permit a bridge means to be engaged in the plastic 25 supports in the upper portion of the expansion void to afford a support for a filling of plastic material for closing the upper portion of the expansion joint.

It is also an object of this invention to provide 30 an expansion joint for concrete constructions said joint comprising a load transmission base unit for closing the lower portion of an expansion void the upper portion of which is closed by means of a plastic filler supported on a bridge 35 means, which spans the upper portion of the expansion void, and has the longitudinal margins thereof engaged in plastic supporting members which are embedded in the adjacent concrete sections of the road facing the expansion void.

40 It is a further object of this invention to provide an expansion joint forming mechanism including releasable plastic supports to be retained in the concrete to afford suitable supports for receiving and supporting a bridge means, 45 which spans the upper portion of the expansion void and serves as a support for a plastic filler.

It is furthermore an object of this invention to provide a concrete road expansion joint forming mechanism including plastic members embedded 50 in concrete sections on opposite sides of an ex-

pansion joint void for receiving and supporting a plastic filler supporting arched bridge unit provided with a longitudinal reinforcing means positioned along a longitudinal center line of the upper portion of the expansion joint filler. 5

Another object of the invention is to provide an expansion joint former including spaced core plates having plastic members removably carried thereon by retaining means which are releasable after the pouring of concrete to permit removal of the core plates and positioning of the retaining means to span the void and interfit one another to form a bridge for the support of a plastic filler. 10

It is an important object of this invention to provide an expansion joint forming mechanism including a load transmission base for supporting a removable core unit having releasably mounted on the sides thereof plastic bars adapted to be partially embedded in the concrete forming adjacent road sections permitting access to be had to the plastic bars when the core unit is removed to allow a reinforced bridge to have marginal portions thereof forced into the plastic bars to hold the bridge in place to support a plastic 20 filler in place. 25

Other and further important objects of this invention will be apparent from the disclosures in the specification and the accompanying drawings. 30

The invention (in a preferred form) is illustrated in the drawings and hereinafter more fully described.

On the drawings:

Figure 1 is a fragmentary vertical sectional view through a portion of a concrete road disclosing an expansion joint forming mechanism embodying the principles of this invention and including releasable plastic supports retainable in the concrete road sections after the removal of 35 the core cap and core members. 40

Figure 2 is an enlarged fragmentary vertical detail section through the upper portion of the expansion joint after the removal of the core cap and core members and showing a plastic 45 filler supported in position upon a reinforced bridge member which spans the expansion void and has the longitudinal margins thereof projected into the plastic supports which are partially embedded in the concrete road sections. 50

Figure 3 is an enlarged fragmentary vertical detail section near the upper portion of an expansion joint forming mechanism and illustrating a modified form of supporting means for supporting plastic bars in position on the sides of 55

the core unit to be embedded in the concrete road sections.

Figure 4 is a fragmentary vertical detail section through the upper portion of an expansion joint forming mechanism illustrating a modified form of supporting members for temporarily supporting plastic bars on the sides of the core unit.

Figure 5 is a similar sectional view with the core members and core caps removed leaving the plastic bars partially embedded in the concrete and showing the plastic bar supports ready to be moved inwardly into engagement with one another.

Figure 6 is a fragmentary detail section similar to that illustrated in Figure 5 showing the bridge members moved into interfitting overlapping engagement with respect to one another to form an arched bridge for the support of a plastic filler for closing the upper portion of the expansion joint.

Figure 7 is a fragmentary vertical detail section through the upper portion of an expansion joint forming mechanism illustrating the plastic bars removably supported on the sides of the core unit by modified supporting means releasably projectable through openings in the core plates.

Figure 8 is a similar sectional view showing the core plates and core caps removed and illustrating an arched bridge member engaged in the plastic bars for supporting a plastic filler in position to close the upper portion of the expansion joint.

Figure 9 is a fragmentary detail perspective view of one of the core plates of the type illustrated in Figure 7 showing a plastic bar held in position on the outer side of the core plate by means of a looped retaining strap, the end members of which are projectable through the plate opening and are bent over against the inner face of the plate. As shown on the drawings:

As clearly illustrated in Figure 1, the expansion joint forming mechanism is illustrated as being embedded between two concrete road sections 1 which form the crown or upper portion of a concrete road, and which are supported upon the road subgrade. The expansion joint forming mechanism for the road or a similar concrete construction includes a base unit comprising an elongated base member consisting of a solid base plate 2 constructed of sheet steel or other suitable material. The longitudinal margins of the base plate 2 are bent upwardly and then inwardly toward one another to form oppositely positioned guide channels 3. The guide channels 3 of the base unit provide oppositely positioned side grooves 4. The margins of the top plates of the guide channels 3 are bent upwardly and are cut away to provide spaced upwardly projecting retaining flanges or tongues 5. The retaining flanges 5 on opposite sides of the base unit are staggered with respect to one another. The upwardly projecting retaining flanges 5 of the base unit are spaced apart to provide a top opening in the base member of the device.

Associated with the base unit is a load transmitting mechanism consisting of a plurality of anchor shoes or holder sections which are movably or shiftably engaged in the base unit, and are arranged longitudinally in offset or staggered relation with respect to one another. The anchor shoes or holders are of substantially identical construction and are arranged with the adjacent shoes reversed with respect to one another 75 as illustrated in Figure 1. Each of the anchor

shoes is constructed of metal and comprises an angle bar including a base flange 6 and an upright flange or web 7 integral with said base flange. Projecting outwardly from each of the upright flanges or webs 7 are anchoring blades 8 which project outwardly leaving the inner sides of the upright flanges or webs 7 flat. The anchoring shoes are staggered with respect to one another to allow the upright flanges 7 to be seated in notches provided in the top flanges of the base section between the retaining flanges or fingers 5 leaving retaining spaces between the inner surfaces of the upright flanges 7 and the outer faces of the retaining flanges or tongues 5 of the base member. Removably supported between the base unit anchor shoes is a void forming core unit comprising a pair of sheet metal plates 9 the lower longitudinal margins of which are held properly spaced apart by being inserted in the spaces between the inner faces of the upright flanges or webs 7 of the anchor shoes and the outer faces of the retaining flanges or tongues 5 as clearly illustrated in Figure 1. Provided in the upper marginal portion of each of the core plates 9 is a row of spaced apertures or openings 10. Releasably engaged against the outer surface of each of the core plates 9 to cover the row of apertures 10 is a plastic strip or bar 11, in the present instance shown as being substantially of a dovetailed cross-section. It will, of course, be understood that the shape of the plastic bar may be any selected shape suitable for the purpose. Each of the plastic bars 11 is provided with a row of transverse openings or apertures 12 which are positioned to register with the core plate openings 10. For holding the plastic bars adjacent the outer surfaces of the core plates 9, tie wires or cords 13 are projected through the plastic bar openings 12 and the core plate openings 10 transversely of the core unit with the ends of the wires projecting upwardly over the tops of the core plates where the wires are twisted one with the other to form a retaining loop for temporarily holding the plastic bars on the sides of the removable core.

Prior to the pouring of concrete to form the road sections, the upper portion of the hollow core unit is temporarily closed by means of a channel or U-shaped closure cap 14 which is used in an inverted position as illustrated in Figure 1 to fit downwardly over the upper margins of the core plates 9 and over the plastic bar retaining looped wires 13. Rigidly secured at spaced intervals within the core closure cap 14 are spacing boxes or members 15.

With an expansion joint forming mechanism in position upon the road subgrade, concrete is poured upon the subgrade on opposite sides of the joint forming mechanism to embed the various members thereof including the plastic bars 11. The deposited concrete forms the adjacent road sections 1. After the concrete has set a desired amount, the closure cap 14 is removed together with the upper spacers 15 forming a part thereof. Edging tools may now be used for providing the rounded corners 16 on opposite sides of the crack or filler void forming the upper portion of the expansion joint. After the removal of the closure cap 14, the plastic bar retaining wires 13 are cut on both sides to release the plastic bars from the core plates. Portions of the wire retaining loops may be left partially engaged with the plastic bars as illustrated in Figure 2 or if desired the retaining wires may be completely pulled out.

With the removal of the retaining wires 13,

the core plates 9 are moved inwardly toward one another and are then pulled upwardly from between the concrete sections 1 leaving the expansion void 17 between the road sections.

5 For the purpose of closing the upper portion
of the expansion void 17, an improved bridge unit
is used. The bridge unit comprises a pair of
inclined bridge plates 18, the outer or lower longi-
tudinal margins of which are slightly deflected
10 to form supporting or base flanges 19 which are
forced into the plastic bars 11 as clearly illus-
trated in Figure 2 to support the bridge unit in
position. The upper longitudinal margins of
the bridge plates or flanges 18 are integrally con-
15 nected by means of a split ridge tube or pipe 20
having a reinforcing or core bar 21 engaged
therein to reinforce the ridge tube 20 and prevent
crushing or indenting of the same in case the
same should be moved too near the upper sur-
20 face of the road to be brought into contact with
vehicle wheels or the like passing over the road.
With the reinforced bridge unit in position as
illustrated in Figure 2, a filling of plastic mate-
rial such as asphalt or the like is poured into
25 the space between the upper portions of the con-
crete sections 1 and above the bridge unit to form
a plastic filler block 22 which covers the bridge
unit and also unites with the plastic bars 11.
The top surface of the plastic filler block 22 is
30 preferably left below the top level of the concrete
sections 1 and slightly above the reinforced ridge
tube 20 of the bridge unit.

35 Figure 3 illustrates a modified form of bridge supporting plastic members and supporting means therefor. In this figure, the core unit members are numbered to correspond with the numbering in Figure 1. In the modified form illustrated in Figure 3, cylindrical plastic bars 23 are positioned on opposite sides of the hollow core unit and are temporarily supported in position by U-shaped hanging wires 24 which engage over the upper margins of the core plates, and have the ends thereof shaped to form retaining hooks 25 which are embedded in the plastic cylindrical bars 23. 40 The wire supports 24 are temporarily covered by the closure cap 14 until after the pouring of the concrete which forms the road sections 1. 45

After the pouring of the concrete, the cap 14 is removed and the edges of the concrete are rounded with suitable edging tools. The supporting wires 24 are then cut to permit the core plates 9 to be removed and allow a filler supporting bridge unit to be engaged in the cylindrical plastic bars 23 to span the upper portion of the expansion void similar to the arrangement illustrated in Figure 2.

Figure 2.

Figures 4, 5 and 6 illustrate another modified form of plastic bar supporting means which in this instance comprises a combination supporting means and a filler supporting bridge mechanism. In this modified form of the device, plastic supporting bars 26 are releasably engaged on the outer sides of the core plates 9 by means of plate hangers 27 the lower margins of which are deflected and project into the plastic bars 26 in the form of supporting flanges 28. The upper margins of the supporting plates 27 are bent to form supporting hooks 29 as illustrated in Figure 4. After the hook supporting plates are engaged on the upper margins of the core plates 9, the core closure cap 14 is engaged in position and the concrete is then poured to form the road sections 1. When the concrete has sufficiently set, the closure cap 14 is removed and the hook shaped portions 29 of the supporting plates 27 are bent

upwardly to permit removal of the core plates 9 leaving the supporting plates 27 in the position substantially that illustrated in Figure 5. The supporting plates 27 are now bent inwardly towards one another with the flanges 29 overlapping each other to form a filler supporting bridge unit as illustrated in Figure 6. A filling of plastic material is now deposited upon the bridge unit to form a filler block 30 for closing the upper portion of the expansion joint.

Figures 7, 8 and 9 illustrate another modified means for temporarily supporting plastic bars 31 on opposite sides of a core unit, the core plates 9 of which are provided with openings 32 at spaced intervals. Partially embedded in the plastic bars 31 at spaced intervals are U-shaped supporting straps 33 the ends 34 of which project out of the plastic bar and project through the core plate openings 32 and are bent over adjacent the plates similar to the arrangement illustrated in Figure 9 for holding the plastic bars temporarily engaged on the outer surfaces of the core plates 9. The expansion joint closure cap 14 is now engaged over the upper margins of the core plates 9 and concrete is then poured to embed the expansion joint forming mechanism to form the concrete sections 1. After the concrete has sufficiently set, the closure cap 14 is removed and the edges of the concrete are properly rounded. The deflected ends 34 of the supporting straps are now bent into the dotted line position illustrated in Figure 7 and the core plates are moved inwardly out of engagement with the supporting members 33 and are removed from between the concrete sections 1 leaving an expansion void between the concrete sections. The ends 34 of the U-shaped straps 33 are now bent into the positions illustrated in Figure 8 and an arched bridge member 35 is engaged in the upper portion of the expansion void 36 and is supported in position by forcing the longitudinal margins of the bridge member into the plastic bars 31 and into the U-shaped portions of the supporting members 33. A filling of plastic material is now deposited upon the bridge 35 to form a filler block 37 for closing the upper portion of the expansion joint. The plastic material forming the filler block 37 finds its way into the U-shaped supporting members 33 and acts as a locking means or binder for assisting in holding the bridge member 35 in position.

One of the features of the present invention is the provision of plastic supporting bars of selective shape temporarily engaged or supported upon the sides of removable core members of an expansion joint forming mechanism. Said plastic bars adapted to be retained in position partially embedded in concrete sections of the road so that after the removal of the closure cap and the core plates of the expansion joint forming mechanism, bridge members of selective shape may be placed in the expansion void to bridge the same with portions of the bridge members forced into the plastic bars similar to the arrangements illustrated in Figures 2, 6, and 8. Attention is also called to the form illustrated in Figures 4 to 6 inclusive wherein the plastic bars are temporarily supported on the core plates by hangers which later on are used to engage one another to form a bridge member for supporting the plastic filler in position to close the upper portion of the expansion void. 50 55 60 65 70

Attention is called to the fact that in this invention expansion joints are provided between adjacent concrete sections of a road with the expansion joint consisting of a load transmission 75

base unit having an expansion void formed thereabove, with the upper portion of the expansion void closed by a plastic filler supported on an adjustable bridge unit the margins of which are supported in plastic bars partially embedded in the concrete road sections. The adjustable load transmission base unit and the adjustable bridge mechanism for closing the upper portion of the expansion void affords an expansion joint 10 permitting the road sections to contract or expand depending upon temperature changes.

It will, of course, be understood that various details of construction may be varied through a wide range without departing from the principles 15 of this invention and it is, therefore, not the purpose to limit the patent granted hereon otherwise than necessitated by the scope of the appended claims.

I claim as my invention:

20 1. A concrete construction expansion joint mechanism including in combination a base, a plurality of load transmission anchor members slidably engaged therewith; a core unit removably supported by the anchor members and removable from the concrete construction to provide an expansion space therein, plastic supporting members of plastic material temporarily carried by the core unit and retainable in position partially embedded in the concrete when the core unit is 25 removed, means for temporarily supporting said supporting members on the sides of the core unit, and a removable closure cap engaged over the last mentioned means and the upper portion of the core unit during the pouring of the concrete 30 to form the concrete construction.

2. A concrete road expansion joint mechanism including in combination a load transmission base, a core unit removably supported therein, bridge supporting bars of plastic material positioned adjacent the outer sides of the core unit, 40 releasable means for temporarily holding the plastic bars in position on the core unit, and a closure cap for removable engagement on the core unit for temporarily enclosing the plastic 45 bar retaining means.

3. An expansion joint mechanism for embedding in concrete and including in combination a base, a core unit removably supported thereby and removable from the concrete to leave a void 50 therein, plastic members releasably secured on the sides of the core unit to remain partially embedded in the concrete when the core unit is removed, and means projecting into the plastic members for closing the upper portion of the expansion joint void.

55 4. An expansion joint mechanism for embedding in concrete and including in combination a base, a core unit removably supported thereby and removable from the concrete to leave a void 60 therein, plastic bars releasably secured to the core unit and retainable partially embedded in the concrete when the core unit is removed, bridge means spanning the expansion void and projecting into the plastic bars and a plastic filler 65 supported on the bridge means for closing the upper portion of the expansion joint void.

70 5. An expansion joint mechanism for embedding in concrete and including in combination a load transmission base, a core unit removably supported thereon and removable from the concrete to leave a void 75 therein, plastic members positioned adjacent the sides of the core unit retainable partially embedded in the concrete when the core unit is removed, means for temporarily holding the plastic members supported

on the core unit during the pouring of concrete, said means releasable after the pouring of concrete to permit removal of the core unit, and filler means supported by the plastic members for closing the upper portion of the expansion joint 5.

6. An expansion joint mechanism for embedding in concrete and comprising a base, a core unit removably supported by the base and filler supporting means of plastic material removably supported on the core unit and releasable therefrom to remain partially embedded in the concrete when the core unit is removed.

7. An expansion joint mechanism for embedding in concrete and including in combination a load transmission base, means for forming an expansion void in the concrete above the load transmission base, plastic members embedded in the concrete and accessible from the expansion void, and filler means projecting from the plastic members for closing the upper portion of the expansion joint void.

8. An expansion void forming device for embedding in a concrete construction, said device comprising a core unit removable from the concrete to leave a void therein, plastic means carried by the core unit, a void closing means, and retaining means for holding the plastic means temporarily associated with the core unit, said retaining means releasable when the core unit 30 is removed from the concrete to leave the plastic means partially embedded in the concrete and accessible from the void to serve as a support for the void closing means.

9. An expansion joint mechanism for embedding in concrete and including in combination a core means removable from the concrete to leave a void therein, plastic means carried by the core means retainable by the concrete and accessible from the void, and means projectable into the plastic means to serve as a support for a filler for closing the upper portion of the void.

10. A road joint former for embedding in concrete and comprising a base, a core unit thereon, plastic members contacting the sides of the core 45 unit, and flexible supports for holding the plastic means temporarily supported on the core unit releasable from the core unit to permit removal thereof, said flexible supports movable into interlocking engagement with one another to span the void resulting from the removal of the core unit and serve as a support for a filler.

11. A road joint former for embedding in concrete and comprising a removable core unit including plastic members contacting the sides of the core unit, and supporting means for holding the plastic members temporarily on the core unit and releasable from the core unit after the pouring of concrete to permit removal of the core unit after which the supporting means are movable into interlocking engagement with one another to span the void resulting from the removal of the core unit and serve as a support for a filler.

12. A road joint mechanism for embedding in concrete and including in combination a pair of oppositely positioned plastic members embedded in the concrete sections on opposite sides of an expansion joint void, bridge means spanning the void and projecting into the plastic members, and a filling of plastic material deposited on the bridge means for closing the upper portion of the expansion joint.

13. An expansion joint mechanism for embedding in concrete and including in combination a

pair of plastic members embedded in the concrete on opposite sides of an expansion joint void and accessible from the void, bridge means spanning the void and projecting into the plastic members, means for reinforcing the bridge means, and a plastic filling deposited upon the bridge means for closing the upper portion of the expansion joint.

14. A concrete expansion joint mechanism for embedding in concrete and including in combination a core unit removable from the concrete to leave a void therein, plastic members contacting the sides of the core unit, and means partially embedded in the plastic members releasably engaging the core unit for holding the plastic members in position during the pouring of concrete and releasable from the core unit to permit removal thereof after the plastic members have been embedded in the concrete.

15. An expansion joint mechanism for embedding in concrete and including in combination removable void forming plates, plastic members contacting the plates, means for releasably holding the plastic members supported on the plates during the pouring of concrete, said means releasable to permit removal of the plates leaving the plastic members embedded in the concrete and accessible from the void resulting from the removal of the core plates, and a filler projecting

into the plastic members for closing the upper portion of the void.

16. A road joint for embedding in concrete and comprising core plates for removable engagement in the concrete, plastic members contacting the outer surfaces of the core plates, releasable means for holding the plastic members in position during the pouring of concrete and releasable to leave the plastic members partially engaged in the concrete when the core plates are removed to form an expansion void affording access to the partially embedded plastic members, and a filler projecting into the plastic members for closing the upper portion of the expansion void.

17. An expansion joint mechanism for embedding in concrete and including in combination a removable void forming core, plastic means releasably engaged thereon to be retained partially embedded in the concrete when the core is removed to form an expansion void, a bridge spanning the expansion void and projecting into the plastic means, a tubular member forming a ridge for the bridge, a reinforcing member in said tubular member, and a filler supported on said bridge for closing the upper portion of the expansion void.

ROBERT R. ROBERTSON.
